UNITED STATES PATENT OFFICE.

ALFRED BARKER DUFF, OF PITTSBURG, PENNSYLVANIA.

SUPERHEATER FOR GAS-PRODUCERS.

SPECIFICATION forming part of Letters Patent No. 764,437, dated July 5, 1904.

Application filed September 19, 1903. Serial No. 173,868. (No model.)

To all whom it may concern:

Be it known that I, ALFRED BARKER DUFF, a subject of the King of Great Britain and Ireland, and a resident of Pittsburg, Allegheny county, State of Pennsylvania, (whose postal address is 5310 Dahlia street, Pittsburg, Allegheny county, State of Pennsylvania,) have invented certain new and useful Improvements in and Connected with Superheating Apparatus for Gas-Producers, (for which application for British Patent No. 16,243, dated July 23, 1903, has been made,) of which the following is a specification.

My said invention has for its object to provide an improved superheating apparatus for gas - producers which shall be simpler, stronger, cheaper, and more efficient than those hitherto in use, while the parts are arranged so that they are more accessible for examination or repair.

In order that the said invention may be fully understood, I hereunto append two sheets of explanatory drawings, to be hereinafter referred to in describing the improvements.

Figure 1 on Sheet 1 of the drawings is a sectional side elevation, and Fig. 2, Sheet 2, a sectional plan, of the improved apparatus shown as applied to a gas-producer.

In the drawings the same reference-letters are used to mark the same or like parts wherever they are repeated.

According to the invention there is provided a vertical shell or casing A of circular form, which is fitted with upper and lower tube-plates A' A² and also with a transverse baffle-plate A³, extending up from the lower tube-plate to within a short distance of the upper tube-plate. On each side of the baffle-plate A³ there is fixed between the tube-plates A' A² two tubes B' B² and C' C², the upper ends of which open into an upper space or box A⁴, formed above the upper tube-plate A', the lower ends of each pair of tubes opening, respectively, into inlet and outlet bottom spaces B³ C³, arranged below the bottom tube-plate A² and formed by a cross-partition plate A⁵. The inlet-space B³ is connected to a brick-lined chamber D, connected to the gas-discharge outlet E' of the producer E, the said chamber being fitted with a stop-valve D', operated by

a wheel and spindle D² D³. Similarly the outlet-space C³ is connected to an outlet-chamber G, fitted with a stop-valve G' and connected to a hydraulic lute-washer or main H, fitted with a gas-discharge pipe H'. The valve-outlet G² opens into a downwardly-extending casing part G³, which dips into the water H² in the washer. The lower ends of the inlet valved chamber D and the bottom spaces B³ C³ are provided with conically-shaped dust-collecting boxes D⁴ B⁴ C⁴, fitted with handled plugs or stoppers D⁵ B⁵ C⁵, while air inlet and outlet connections J' J² are fitted to the circular shell A at a point a little above the lower tube-plate A², the outlet J² being connected to the blower casing or grate part of the producer E. A manhole-door A⁶ is fitted to the top of the circular casing A, opposite each vertical tube, and similar doors A⁷ A⁸ are provided on the side of the casing, so that entrance can thus be conveniently obtained for examination or repair of the parts, ample room being left between the parts, so as to allow a workman to get about with facility and perform the necessary examination or repair.

The action of the apparatus is as follows: The inlet and outlet gas-valves D' D' being opened, gas formed in the producer E passes out by the upper outlet E' into the inlet valved chamber D and flows into the inlet - bottom space B³. From this space it flows upward through the first pair of tubes B' B² into the upper space or box A⁴. The gas then flows down through the second pair of tubes C' C² into the outlet-bottom space C³, from which it is discharged through the valved outlet G², the gas passing under the edges G⁴ of the depending casing G³ and then bubbling up through the water H² into the flue-space H³, from whence it passes out through the discharge-pipe H'. While the hot gas is thus passing through the vertical up-comer and down-comer tubes B' B² and C' C² air or air and steam for the support of combustion in the producer E is also flowing through the circular casing A in contact with the outer surface of the tubes, so that it becomes superheated before entering the blower casing or grate, while the gas becomes partly cooled. The baffle-plate or air-deflecting piece A³

causes the entering air to take a regular upward and downward course among the tubes C' C² and B' B² before passing to the outlet J², so that it comes thoroughly in contact with 5 the tube-surfaces, and thereby gets effectively heated before passing to the blower casing or grate.

The improved apparatus as hereinbefore described possesses considerable advantages 10 over those hitherto in use. For example, the plan of having simply a single set of up-comer and down-comer gas-tubes B' B² and C' C² is an important advance on previous arrangements, as by this means the hot gas is thus 15 made to take only one upward and downward sweep through the tubes on its way to the outlet, while, owing to the increased area of the tube-passage, the gas travels at a much slower rate, which gives better conditions for trans- 20 ference of heat and for the collection of dust from the gas. Besides, as there is a separate dust-box for each of the up-comer and down-comer tubes, there is no danger of the dust being swept up out of the box into a tube, as is 25 possible under present existing arrangements where a dust-box is made common to both an up-comer and down-comer tube. The shape and construction of the apparatus also increases its strength and durability, and pre- 30 vents buckling or collapsing of the parts, which is so liable to happen with superheating apparatus as hitherto constructed, while the ease with which it can be examined and repaired lessens labor and altogether combines to make 35 the apparatus much more serviceable for the purpose required.

I claim as my invention—

1. Improved superheating apparatus for use in connection with gas-producers, comprising, 40 in combination, a circular casing, or shell, a manhole-door therefor, upper and lower tube-plates therein, an upper box part arranged above the top tube-plate, and a manhole-door in said box, a set of up-comer and of down-comer 45 gas-tubes fitted between the tube-plates, the area of the tubes and the space between them and the casing being sufficient to admit of cleaning and repairs without dismantling, a baffle or air-deflecting plate fitted between the respective sets of tubes, separated inlet and outlet 50 bottom spaces arranged within the shell below the bottom tube-plate and connected respectively to the up-comer and the down-comer sets of tubes, a dust-box for each tube fitted

to the bottom spaces, an inlet valved chamber, 55 with dust-box attached, connected to the inlet-bottom space and to the main gas-outlet of the producer, and an outlet valved chamber, an inlet and an outlet for air, or air and steam, for combustion in the producer. 60

2. In superheating apparatus for use in connection with gas-producers, a circular casing or shell, upper and lower tube-plates therein, extending entirely across said shell, an upper box part arranged above the top tube-plate, 65 a set of up-comer and of down-comer gas-tubes fitted between the tube-plates and communicating with each other only through the upper box part, an inlet from the producer to the up-comer tubes, said up-comer tubes being of much greater cross-section than said inlet, a separate dust-box arranged on the casing for each tube, and means for causing the air, or air and steam, for combustion to come in contact with the outer surfaces of the tubes. 70

3. Superheating apparatus for use in connection with gas-producers, comprising, in combination, a circular shell, upper and lower tube-plates therefor, extending entirely across said casing, two up-comer tubes and two down-comer tubes, the lower ends of each pair ending in a dust-collecting box, sufficient room being left through and around each gas uptake and downtake tubes within the outer shell to admit of a workman for repairs or cleaning, 85 a manhole in the side and in the top of said shell. 80

4. Superheating apparatus for use in combination with gas-producers, comprising a circular casing, upper and lower tube-plates, 90 and up-comer and down-comer tubes therein, a dust-box at the bottom of each set of tubes, the area through the two up-comer tubes and the two down-comer tubes being much greater than the area of the gas-supply pipe from the 95 producer so that the speed of gas through the two tubes is less than that of the gases flowing into the superheater from the producer, whereby the dust in the gases is released and falls into the dust-chambers provided at the 100 base of each double row of tubes.

In testimony whereof I have signed my name to this specification in the presence of two subscribing witnesses.

ALFRED BARKER DUFF.
